SPACER ELEMENT FOR TYPOGRAPHICAL MACHINES

Arthur G. Sperry, Hollis, N. Y., assignor to Intertype Corporation, Brooklyn, N. Y., a corporation of New York

Application June 13, 1939, Serial No. 278,835

24 Claims. (Cl. 199—22)

The present invention relates to improvements in typographical machines and more particularly to those of the general class disclosed in U. S. Letters Patent 436,532 granted September 16, 1890, wherein circulating character bearing matrices and expansible spacebands released respectively from suitable storage receptacles in response to manipulation of a keyboard are composed into lines, the lines being delivered to a vertically movable transporter which presents them, while clamped endwise, before a slug casting mold and thereafter raises the lines to a transfer channel where the matrices and spacebands are separated and subsequently returned to their places of storage.

The present invention deals particularly with improvements relating to the thin spacer elements commonly known as "hair spaces" which are inserted in the composed line by hand, either between each matrix to produce letter spacing or between words to augment the spacing provided either by expansible spacebands or blank space matrices, the invention being directed to "hair spaces" of an improved design and means for enabling their distribution at the time of transfer of the line in an orderly manner.

Hair space elements heretofore employed conform in size and shape to the usual character bearing matrices including the usual upper and lower ears projecting edgewise, but being devoid of the combination distributor teeth provided on the matrices. As well known to those familiar with machines of the class referred to, when a line is moved into the transfer channel the matrices (which have an over-all edgewise dimension less than the width of the channel) are fed onto the ribbed bar of the usual second elevator which is projected into the channel at the proper time to receive and support the matrices by their combination teeth and to raise them out of the channel upwardly to the distributor. Meanwhile, the spacebands, which are devoid of teeth but have lugs at their upper end that project edgewise further than do the ears on matrices, are left hanging by these lugs on side rails of the channel until a lever having a pawl device arranged to engage the lugs of the last spaceband to the left of the group thereof operates to move the spacebands along the rails and into a spaceband storage box at the right end of the channel.

Since the hair spaces are of the same width as the matrices and have neither teeth to support them on the second elevator bar nor lugs projecting far enough to engage the side rails of the channel as do the lugs on spacebands, the hair spaces simply fall by gravity and at random between the side walls of the channel during the transfer of the line, it being intended that they tumble forwardly through an elongated opening in the front wall of the channel into a so-called

quad box secured to the front of the channel adjacent to the bottom thereof.

This haphazard disposal of hair spaces out of a line has long been a constant source of annoyance and cause of delays since the hair spaces frequently lodge in various positions in the bottom of the transfer channel where they obstruct the progress of spacebands or they tumble clear of the quad box and fall on the floor where they are lost or damaged.

The object of the present invention is to overcome the above objections arising from non-support of hair spaces by providing for their support on the usual spaceband supporting rails during circulation in the various channels of the machine including the transfer channel and the invention further provides for the complete and orderly distribution of hair spaces to a definite place of storage. To these ends the invention provides hair space elements with a V-shaped notch at the upper end thereof and having an upper set of lugs corresponding substantially in location and extent of projection to the supporting lugs on expansible spacebands, and lower lugs or ears corresponding in location and projection to the similarly located ears on character matrices, the upper lugs serving to support the hair spaces on the usual spaceband supporting rails of the machine and the lower lugs aiding to sustain them upright on the matrix supporting rails of the assembling elevator. The invention further provides means such as teeth in the hair spaces and downwardly inclined rails on the usual center bar of the spaceband box, engagement of the teeth on such rails providing support for the hair spaces in the spaceband box independent of the support afforded thereto by the spaceband supporting rails therein. The hair spaces thus supported gravitate toward the front of the box until stopped by a spaceband arrested in the usual manner at the forward end of the box. Upon release of such spaceband, however, the invention provides for escape of the succeeding hair spaces forwardly, an opening being provided in the front wall of the box of suitable shape and location to permit the free passage therethrough of hair spaces upon gravitation to the foremost position in the box, and a receptacle being provided for receiving and retaining the hair spaces in a stack from which they may be removed by hand when needed. The supporting teeth on the hair spaces may be located as desired but preferably either at the apex of the V-shaped notch therein or at the upper end of the notch substantially in alignment with the supporting lugs. In the latter case a further feature of the invention is the provision in the spacebands of notches in alignment with such teeth in the hair spaces to afford clearance for the hair

space supporting rails provided on the center bar of the spaceband box.

In the accompanying drawings the invention is shown in two forms and by way of example, but 5 obviously changes and variations may be made therein and in the mode of application without departing from the spirit of the invention. It is to be understood, therefore, that the invention is not limited to any specific form or embodiment 10 except insofar as such limitations are specified in the appended claims.

Referring to the drawings:

Fig. 1 is a partial front elevation of a typographical machine embodying the present invention. 15

Fig. 2 shows in side elevation a standard matrix and spaceband and hair spaces according to the invention.

Fig. 3 is an enlargement of the spaceband box 20 in Fig. 1 with the front plate removed to show the hair space supporting rail and storage receptacle according to the invention.

Fig. 4 is an end elevation viewed from the right of the spaceband box in Fig. 3.

Fig. 5 is a section of the transfer channel taken 25 on the line 5—5 in Fig. 1.

Fig. 6 is a fragmentary section of the spaceband box taken on the line 6—6 in Fig. 1.

Fig. 7 is an enlargement showing details of 30 the spaceband and hair space supporting rails in Fig. 3.

Fig. 8 is a section through the usual assembling elevator with the hair space according to the invention supported therein.

Fig. 9 is a side elevation of the jaws of the 35 usual line transporter in Fig. 1 showing the hair space of the invention supported therein on the usual spaceband rails, the transporter being shown in casting position.

Fig. 10 is similar to Fig. 6 but shows a modified 40 form of hair space and supporting rails therefor in the spaceband box.

Fig. 10a is a fragmentary view of the upper 45 end of a spaceband modified as indicated in Fig. 10 to suit the modified form of hair space therein.

Similar parts are designated by the same reference characters in the different figures.

The present invention is applicable generally 50 to typographical machines of the class illustrated wherein 1 represents a matrix magazine from which character bearing matrices stored therein fall by gravity between guides 2 of a vertical raceway or assembler front 3 in response to manipulation of keys 4 of a keyboard, the matrices being picked up by an inclined belt 5 traveling past the lower ends of guides 2 and thereby directed over a rotating star wheel 6 into an upright edgewise position where they rest on opposed rails 7 and 8 respectively on the front and rear walls 9, 10 of the assembling elevator 11.

At desired intervals during the composition of the line a spaceband key 12 is operated to release the usual wedge shaped expandible spacebands Y from the spaceband storage box 13 and upon completion of the line the elevator 11 is raised to position the line between fingers 14, 14^a of the so-called delivery slide which at the proper time is released to carry the line leftward through the delivery channel 15 into the vertically movable line transporter 16, the jaws 17 and 18 of which at this time are in line receiving position represented by dot-dash lines in Fig. 1. After thus receiving the line the transporter moves downwardly to present the line while supported on suitable rails therein and clamped endwise between

opposed vise jaws 19, 19^a, before a mold M, Fig. 9, in which a type slug is cast against the characters on the matrices. Following the cast the transporter elevates the line to transfer position (shown in full lines in Fig. 1) where the line is pushed to the right out of the transporter by movement of a pusher 20 from the dot-dash position to the full line position in Fig. 1, the second elevator ribbed bar 21 at this time being projected into the transfer channel 22 to receive and support the matrices by their usual combination teeth as the line is thus pushed into the channel 22 and to elevate the matrices to the usual distributor mechanism of the machine, not shown. During such removal of the matrices, the spacebands Y are supported in the transfer channel 22 by engagement of lugs y at the upper end thereof over side rails 23, 24 of the channel and thereafter are moved into compact relation by a second action to the right of the pusher 20 (somewhat to the right of the full line position in Fig. 1) whereupon the usual spaceband transfer pawl 25 moves to the left until the hook or shoulder 26 thereof engages over the lugs of the last spaceband to the left in the channel. The pawl then moves all the way to the right (shown by dot-dash lines in Fig. 1) to thus move the spacebands along the rails 23, 24 until they arrive on the inclined rails 27, 28 in the spaceband box 13 over which rails they slide by gravity, the leading spaceband finally resting at its upper end against the inner face of the front wall or plate 29 and at its lower end against the spaceband release pin 30.

The construction and mode of operation of the parts just described is well known so that it is deemed sufficient hereinafter merely to refer to details thereof in connection with the novel hair space of the present invention and the means provided by the invention for accomplishing an orderly distribution thereof.

First, however, it will be helpful to review briefly the difficulties encountered in the use of the ordinary hair spaces which, as previously stated, conform in size and shape to the usual character bearing matrices X but are devoid of the distributing teeth x provided on the matrices and thus find no means of support when a line containing them is slid into the transfer channel 22. Referring to Fig. 5, such hair spaces Z are shown by dot-dash lines resting in haphazard fashion in the bottom of the transfer channel 22 instead of in the quad box 8 which is a receptacle especially provided at the front of the channel for catching these hair spaces as they fall by gravity during the transfer of a line, it being the intention that they be deflected forwardly by the inclined surface 22^a into the quad box. Frequently, however, they are deflected clear of the box entirely and fall to the floor or else they fall and lodge in such inclined, edgewise or flatwise positions along the bottom of the channel that they obstruct the passage of spacebands.

According to the present invention a hair space element is provided having a set of supporting lugs at the upper end thereof which conform substantially in size and location (relative to the upper ears on matrices) to the lugs y on the expandible spacebands Y thus enabling these elements to be supported during the operations of assembly, line delivery, casting and line transfer on the same rails as are provided in the machine for supporting the spacebands. At the lower end, there is provided a set of lugs (except as hereinafter pointed out) corresponding to the

lower ears on matrices. Such hair space is preferably also provided with a set of opposed teeth in the V-shaped notch at the upper end thereof and the usual center bar of the spaceband box is provided with a corresponding pair of rails to cooperate with the teeth on the hair spaces to thus accomplish an orderly distribution of the latter into the spaceband box together with the spacebands.

10 Referring to Fig. 8, the hair space 31 of the present invention is shown in the assembling elevator 11. Immediately behind it is a standard character bearing matrix X with distributing teeth x and behind the matrix is a standard 15 spaceband Y. It will be observed that the hair space 31 is provided at its upper end with a set of lugs 32, 33 projecting edgewise therefrom substantially to the same extent and of the same size as lugs y on the spaceband Y, and at its 20 lower end with a set of lugs 34, 35 corresponding to the lower set of ears on the matrix X. Moreover, these upper and lower sets of lugs are spaced apart a distance greater than the spacing between the corresponding upper and lower 25 lugs on the matrix, the upper lugs being located at such height as to project over the walls 9, 10 of the assembling elevator when the lower lugs of the hair space rest on the normal matrix supporting rails as shown.

30 Hair spaces 31 may be inserted by hand at desired points in a composed line of matrices as heretofore, the front wall 9 or "gate" of the elevator being arranged to swing forwardly in the usual manner (see dot-dash lines in Fig. 8) 35 to facilitate such insertion as well as other adjustments in a line preparatory to delivering it to the casting mechanism of the machine. The hair space 31a, Fig. 2, differs from the hair space 31 only in that lower front lug is omitted so as to clear the usual auxiliary rail 9a in the assembling elevator 11 when the rail is brought into use, this rail when desired being projected inwardly by operating the handle 11a so that 40 matrices may be aligned at a level suitable for casting against the lower character thereon in well known manner. Thus, hair spaces 31 or 45 31a may be employed as required, the upper lugs on either form engaging over the walls 9, 10 of the assembling elevator to support them in. 50 the same manner and at the same level as the spacebands are supported in the elevator.

In Fig. 9 the hair space 31 is shown supported in the jaws 17, 18 of the line transporter 16 by engagement of its upper lugs 32, 33 with the usual spaceband supporting rails 38, 39, it being understood that these rails are coextensive with like rails in the delivery channel 15 when the jaws 17, 18 of the transporter 16 are in line receiving position (see dot-dash lines in Fig. 1) and with the top of walls 9, 10 of the assembling elevator when the latter is raised to deliver a line to the transporter. From the description thus far it will be seen that hair spaces 31 or 31a 60 are supported during the assembly, delivery, and casting operations on the same rails that support the usual spacebands.

At the line transfer position of the transporter 16, shown in full lines in Fig. 1, the rails 38, 39 in the jaws 17, 18 align with the spaceband supporting rails 23, 24 of the transfer channel 22. By virtue of the lugs 32, 33 herein provided on hair spaces 31 and 31a such hair spaces, like the spacebands Y, hang on the rails 23, 24 as shown in Figs. 1 and 5. Thus, instead of falling 70 haphazardly to the bottom of the channel in

the manner of the ordinary hair spaces Z during the line transfer operation, the hair spaces 31 or 31a are fully supported during transfer and the invention provides means now to be described for accomplishing their orderly distribution into the usual spaceband box together with spacebands.

Such means comprises a set of opposed teeth 40 formed at the apex of the V-shaped notch in the hair space and longitudinally extending 10 cooperating rails 41 along the bottom of the center bar 42 of the spaceband box and extending beyond the front wall thereof. The teeth 40 are located below the level of the lowermost 15 teeth on the matrices in order to clear the ribs 10 on the second elevator bar 21 during transfer of a line as best shown in Fig. 5. As the hair spaces and spacebands are moved along the rails 23, 24 of the transfer channel 22 by the pawl 25 they arrive on the downwardly inclined rails 20 27, 28 in the spaceband box and slide by gravity 25 along these rails, the teeth 40 in the hair spaces engaging the rails 41 at the left end of bar 42 as they enter the box while the lugs 32, 33 on the hair spaces and the lugs on the spacebands 25 ride on the rails 27, 28, see Fig. 6. It is not essential, however, that lugs 32, 33 contact with rails 27, 28 once the teeth 40 are engaged with the rails 41 since the latter then afford all necessary 30 support for the hair spaces. As a matter of fact the rails 41 may start at some point well beyond the left end of the bar 42 in which case lugs 32, 33 would support the hair spaces on the rails 27, 28 until the teeth 40 engaged the shortened 35 rails 41.

In Figs. 3 and 7 a group of hair spaces 31 and spacebands Y are shown at rest in the spaceband box 13, the elements behind the leading spaceband being retained against sliding to the right by reason of arrest of the leading spaceband, as 40 usual, by engagement of the lugs at its upper end against the inner face of the front plate 29 and toward the bottom against the release pin 30. For reasons not concerned with the present invention but only with the fall of spacebands 45 when released, the rails 27, 28 are abruptly inclined toward their lower ends and terminate clear of the inner side of the front plate as best shown in Fig. 7. The center bar 42 is provided with a thin depressor blade 44 which contacts 50 the bottom of the V-shaped notch in the spacebands to urge them downwardly, for reasons hereinafter pointed out, in the event that they should not settle of their own weight to the lowest possible level as they slide toward the lower 55 ends of the rails 27, 28.

As well known, at each operation of the release pin 30 the leading spaceband in the box swings to a vertical position and falls by gravity through the usual chute 29a, the lugs y of the 60 released spaceband being guided behind the front wall or plate 29 of the chute as indicated by dotted lines in Fig. 4. According to the invention the usual opening 45 in the front plate 29 is widened by symmetrical recesses 46, 47 so 65 located as to lie opposite the upper lugs 32, 33 on a hair space supported immediately behind the front plate on rails 41 and the opening is similarly widened opposite the lower lugs of such hair space by recessed or cut back portions 48, 70 49. The width of these recessed portions is slightly greater than the over-all width of a hair space across the upper and lower lugs respectively and the center bar 42, or at least the hair space supporting rails 41 thereon, project through 75

the opening 45 to thereby guide the hair spaces out of the box, the recessed formation of the opening in the front plate permitting free passage of the hair spaces therethrough. The purpose of 5 the downward urge imparted to spacebands by blade 44 as they approach the lower ends of rails 21, 28 will now be clear in that it assures that the lugs of a leading spaceband lie below such level as would permit them to pass through the 10 widened portion produced by the recesses 46, 47 in the front plate 29.

When a hair space becomes the leading element in the spaceband box (due to release of a spaceband positioned ahead of it) it immediately 15 gravitates along the ribs 41 toward the front plate 29, the weight of succeeding hair spaces or spacebands or both aiding the gravitating movement and the widened portions of the opening 45, due to the aforementioned recesses, providing 20 for the free exit of one or of several hair spaces as the case may be through the opening. The hair spaces thus freed gravitate and pile up in an inclined stack in a suitable receptacle 58 secured to the cover plate 28 such receptacle having 25 side and bottom walls and being open at the front to afford ready access to the hair spaces therein. This is best shown in Figs. 1 and 3, the latter figure showing a hair space 34 in free flight after having escaped through the opening 45 and the 30 former showing several hair spaces stacked in the receptacle 58 from which they may be removed by hand as needed. As many hair spaces become freed from the spaceband box after release of a spaceband as may lie between the 35 released spaceband and the next spaceband. Thus a spaceband will always be the actual leading element ready as usual to be released in response to actuation of the spaceband key 12. The hair spaces 31 or 31^a are provided with an 40 elongated slot 51 in order to clear the spaceband depressor blade 44 as they gravitate on the rails 41.

The supporting teeth in the hair spaces may be located at positions other than at the apex 45 of the V-shaped notch therein and this arrangement may be advantageous or even preferable for certain adaptations of the invention. In fact, the teeth may even be located above the level of the upper lugs if desired by merely 50 elongating the body of the hair space. In Fig. 10 teeth 52, similar to teeth 46 are provided, such teeth being located at the upper end of the hair spaces substantially at the level of the supporting lugs thereon. In such case rails 53 are provided on the center bar 42, these rails being 55 located at the proper level along the sides of the bar to cooperate with the teeth 52. According to the invention the standard spaceband Y is modified to suit this arrangement of supporting 60 teeth and rails. This is shown in Fig. 10a wherein the spaceband Y is provided with notches 54 of suitable size to clear the rails 53.

From the foregoing it will be evident that the lugs as herein provided at the upper end of hair 65 spaces enable the latter to find support on all of the usual spaceband supporting rails of the machine during assembly, delivery and transfer of a line and moreover, these lugs together with the teeth in the hair spaces and cooperating rails 70 in the spaceband box enables an orderly distribution of the hair spaces together with the spacebands, thus overcoming the objections encountered with the ordinary hair spaces Z. The means provided for permitting escape of the hair 75 spaces from the spaceband box avoids conflict

with or disturbance to the ordinary function of the spaceband box or the release of spacebands therefrom. The lower lugs on the hair spaces aid to sustain them upright on the matrix supporting rails of the assembling elevator, that is, such lugs aid in supporting the hair spaces when the gate 5 of the elevator is swung open, it being apparent that at such time the upper front lugs momentarily lose the support afforded by the front wall 9. 10

I claim as my invention:

1. In a typographical machine having channels provided with opposed rails for the support thereon of expandable spacebands circulating edgewise through the channels, a non-expandable spacer element having means adapted to support it during circulation on said spaceband supporting rails. 15
2. In a typographical machine having channels provided with rails located at a given level for engagement thereon of the supporting lugs of expandable spacebands circulating edgewise in said channels, a non-expandable spacer element having lugs corresponding to the lugs on the spacebands to thereby support it for edgewise circulation in said channels at the level of the spacebands. 20
3. In a typographical machine having channels provided with rails located at different levels in the opposed walls thereof for the support thereon respectively of matrices and expandable spacebands circulating through said channels, a non-expandable spacer element having means adapted to support it for circulation at a level corresponding to the level of the spaceband supporting rails. 30
4. In a typographical machine having channels provided with rails for the support of expandable spacebands by engagement on said rails of lugs projecting edgewise from the spacebands, a non-expandable spacer element having edgewise projecting lugs corresponding to the lugs on the spacebands and adapted to support said element on the spaceband supporting rails in said channels. 40
5. In a typographical machine having an assembling elevator provided with fixed and adjustable rails for the support of matrices edgewise thereon at different levels according to the position of the adjustable rail, and provided also with spaceband supporting rails located at a level 50 above that of the matrix supporting rails, a hair space element having means adapted to effect its support on the spaceband supporting rails irrespective of the level at which the matrices are supported. 45
6. In a typographical machine having a line transfer channel and a spaceband box, each provided with rails for the support of circulating spacebands and hair space elements, said box having means distinct from said rails adapted to support the hair space elements in the box independent of the support afforded thereto by said rails. 55
7. In a typographical machine having a line transfer channel and a spaceband box each provided with rails forming a continuous support for spacebands and hair space elements moved along the channel and into the box, said box having additional rails adapted to engage the hair space elements upon entering the box and support said 60 elements therein. 65
8. In a typographical machine having a spaceband box provided with distinct sets of rails adapted respectively to support spacebands and hair space elements in the box. 70

9. In a typographical machine having a spaceband box provided with downwardly inclined rails for supporting spacebands thereon in depending fashion, a center bar for guiding the spacebands while gravitating on said rails, and a set of rails on the center bar adapted to engage and support hair space elements thereon in depending fashion.

10. In a typographical machine having a spaceband box with a front wall and provided with downwardly inclined spaceband supporting rails terminating clear of said wall to provide a passage at the rear of the wall for the escape of spacebands gravitating on said rails, a set of similar downwardly inclined rails for supporting hair spaces in the box, said latter rails extending beyond the front wall thereof and said wall having an opening therein for the passage therethrough of hair spaces gravitating on the hair space supporting rails.

11. In a typographical machine having a spaceband box provided with different sets of downwardly inclined rails for supporting spacebands and hair spaces respectively in depending fashion in the box, a device for releasing the spacebands, a wall spaced from the lower end of the spaceband rails to provide a passage for the escape of a spaceband when released, and an opening in said wall for the passage therethrough of the hair spaces.

12. In a typographical machine having a spaceband box with a front wall and provided with distinct sets of inclined rails for supporting spacebands and hair spaces respectively and for guiding them by gravity toward the front wall of the box, said wall having means for arresting the spacebands and an opening widened by recesses at the upper and lower ends thereof for the passage through the opening of hair spaces gravitating on their supporting rails, and said hair space supporting rails extending through said opening to thereby guide the hair spaces forwardly out of the box.

13. In a typographical machine according to claim 12 including as a further element the center bar of the spaceband box, wherein the hair space supporting rails are located on the center bar and the spaceband supporting rails are located on the side walls of the box, and wherein the latter rails terminate clear of the spaceband arresting means and below the level of the upper recesses in the opening in the front wall of the box.

14. In a typographical machine according to claim 12 including as a further element the center bar of the spaceband box, wherein the spaceband supporting rails terminate clear of the front wall of the box and the center bar is provided with a blade disposed in alignment with the apex of the V-shaped notch in the spacebands and engageable therewith to depress the spacebands below the level of the upper recesses in the opening for the hair spaces in the front wall of the box.

15. In a typographical machine according to claim 12 wherein a receptacle is provided at the forward side of the front wall to catch the hair spaces passing through the opening in the wall, said receptacle having side and bottom walls adapted to guide and retain the hair spaces in a stack and having an opening at the front to afford access to the hair spaces.

16. In a typographical machine having a

spaceband box with a front wall and downwardly inclined rails for supporting spacebands gravitating thereon to a position of rest against the inner face of said wall, a similarly inclined rail for supporting hair spaces gravitating thereon to a position of rest against the spacebands, spaceband releasing means, and an opening in the front wall for the passage therethrough of the hair spaces upon release of a spaceband.

17. A hair space element adapted for circulation in the matrix and spaceband channels of a typographical machine, said element having at its lower end edgewise projecting lugs corresponding to similar lugs on matrices, and having at its upper end edgewise projecting lugs corresponding to the supporting lugs on spacebands and adapted to support said element during circulation in said channels.

18. A hair space element adapted for circulation in the matrix and spaceband channels of a typographical machine, said element having upper and lower sets of edgewise projecting lugs spaced apart a distance greater than corresponding upper and lower sets of lugs on matrices and the upper lugs on said element projecting edgewise to an extent greater than the lower lugs thereon or than the extent of projection of either set of lugs on the matrices.

19. A hair space element adapted for circulation in a typographical machine, said element having supporting lugs at its upper end corresponding to the lugs on expansible spacebands and having means distinct from said lugs for supporting it in the spaceband box of said machine.

20. A hair space element according to claim 19 wherein the means for supporting it in the spaceband box comprises opposed teeth or the like in the V-shaped notch at the upper end of the element.

21. A hair space element according to claim 19 wherein the means for supporting it in the spaceband box comprises opposed teeth in the V-shaped notch at the upper end of the element, and wherein said teeth are located at the apex of said notch and below the level of corresponding teeth in matrices.

22. A hair space element according to claim 19 wherein the means for supporting it in the spaceband box comprises opposed teeth in the V-shaped notch at the upper end of the element and wherein said teeth cooperate with rails provided on the center bar of the spaceband box.

23. A hair space element according to claim 19 wherein the means for supporting it in the spaceband box comprises opposed teeth located at the upper end of the element substantially at the level of the supporting lugs thereon and wherein said teeth cooperate with rails provided on the center bar of the spaceband box.

24. In a typographical machine having a spaceband box provided with downwardly inclined rails in the side walls thereof for supporting the lugs of spacebands, an inclined center bar engageable in the V-shaped notch between the lugs in the spacebands for guiding them while gravitating on the rails, hair space supporting rails projecting from the sides of the center bar and located at the level of the supporting lugs on the spacebands, and notches in walls of the V-shaped notch in the spacebands to permit clearance for the rails projecting from the center bar.

ARTHUR G. SPERRY,
